G. M. CHENEY

YARN TENSIONING FOR LOOM SHUTTLES

Filed March 26, 1925

UNITED STATES PATENT OFFICE.

GEORGE M. CHENEY, OF SOUTHBIDGE, MASSACHUSETTS, ASSIGNOR TO LITCHFIELD SHUTTLE COMPANY, OF SOUTHBIDGE, MASSACHUSETTS, A CORPORATION OF MASSACHUSETTS.

YARN TENSIONING FOR LOOM SHUTTLES.

Application filed March 26, 1925. Serial No. 18,581.

This invention relates to loom shuttles, and is more particularly concerned with the provision of means for effecting the desired tensioning of the yarn as it is being delivered from the shuttle in the weaving operation.

With this end in view the invention comprises, in combination with the channelled forepart of a shuttle, tensioning means located in said channel and comprising opposed yarn-engaging members arranged to receive the yarn from the threading plates or members and to exert a conjoint yielding pressure upon the yarn passing between them to the shuttle outlet or delivery eye. A further feature of the invention comprises any conveniently arranged means for readily adjusting the tensioning action of the opposed tensioning members upon the interposed yarn. These and other features of the invention will be particularly described in the following specification and will be defined in the claims hereto annexed.

In the accompanying drawings I have illustrated two specifically different forms of construction embodying the principles of this invention, in which:

Figure 1 is a plan view of the forward end or forepart of the shuttle equipped with my improved tensioning means.

Figure 2 is a transverse vertical section, as viewed on the plane crossed by the arrows in Figure 1.

Figure 3 is a longitudinal sectional view through the forepart of the shuttle, illustrating the same form of device as in Figures 1 and 2.

Figures 4, 5 and 6 are corresponding views illustrating a modified construction of tensioning means embodying the invention.

For the purposes of illustration I have shown a loom shuttle 1, whose forepart is provided with a longitudinal medial channel indicated at 2, which at its forward end communicates with a lateral or outlet passage leading to the delivery eye or yarn-outlet 5, in the side of the shuttle.

The threading plates 3 and 4 overhang the shuttle in such a way as to guide the yarn into the medial channel and outlet passage, the tensioning means being so arranged that, as the yarn is guided into the medial channel it is also inserted into the tensioning

device which retains it there, as will be presently described.

In the throat or rear portion of the medial channel 2 is located the tensioning means which comprises a base member 6, preferably of cylindrical form, provided with an upstanding yarn-engaging pin 8 arranged to one side of the center. The opposite side of the base is slotted to permit the insertion of a movable yarn-engaging member 7 which is pivoted upon a transverse fulcral pin 7^a driven transversely through the slotted portion of the base member.

As indicated in Figures 1 and 2, the opposed faces of the yarn-engaging tensioning members, instead of being flat, are formed so that one projects slightly into the other. To effect this partial inter-matching of the two members the inside or yarn-engaging face of the movable member 7 is somewhat concaved to partially embrace the convex opposing face of the other member 8. Furthermore, the upper ends of both members are bevelled or sloped inwardly to guide the yarn in between the two tensioning members when the yarn is threaded into the shuttle. It will also be observed that the vertical edges of the concaved portion of the movable tensioning member 7 are cut away to leave overhanging hook-like ledges 7^b, which project beyond or overhang the inner face of this member and, therefore, act as stops or shoulders to prevent the accidental escape of yarn from its normal and proper position between the two tensioning members.

The movable or pivotal member 7 is slightly pressed toward the opposing stationary member 8, by means of a thrust-spring 10 interposed between a set screw 9, inserted in a lateral bore through the side wall of the channel, and the outer face of the movable member 7. The set screw 9 lies wholly inside the wall of the shuttle and is provided, at its inner end, with a small projection or boss penetrating the helical spring to aid in positioning the latter. The tension may be easily varied by turning the adjusting screw 9 farther inward or outward, as it is desired, to increase or diminish the tension on the yarn.

In case it is preferred to effect the adjustment of the yarn tension through the bottom instead of through the side wall of the shuttle, I provide a modified form of mov-

able member, as shown in Figures 4, 5 and 6. In this case the vertical portion 17 of the movable member is, in all essential respects, like the movable member 7 but it is provided on its outer face with an extension or arm 17^a, extending horizontally and transversely of the shuttle. In this case the adjusting screw 9 and the tensioning pin 10, are mounted in a vertical bore 10 passing in through the bottom of the shuttle in appropriate position to allow the tensioning spring 10 to press against the outer end of the projection or arm 17^a so as to press the arm inward yieldingly to produce 15 the same effect as in the form previously described.

The base 6 of the tensioning member is held against both torsional and vertical displacement by means of an anchoring pin 6^a, 20 driven transversely through that portion of the shuttle which receives the base so as to engage the transverse groove or notch formed in the forward portion of said base.

What I claim is:

1. In a loom shuttle, the combination with 25 a shuttle body whose forepart is provided with a medial longitudinal yarn-channel having communication with a thread-eye, of threading members overhanging said channel, yarn-tensioning means located in the rear portion of said channel and embracing an upright post secured in a socket in the bottom of the channel, a tensioning jaw pivotally mounted thereon to swing about 30 a longitudinal fulcral pin supported by said post in a plane transversely of the shuttle toward and away from said post, a compression spring mounted in a recess in the 35 bottom of the shuttle to exert pressure 40 against said pivoted jaw, and an adjusting

screw also mounted in said recess to abut against and vary the compression of said spring.

2. A self-threading shuttle and yarn-tensioning device embracing an upright post 45 having an enlarged base portion adapted to be secured in a socket in the bottom of the shuttle, a pivotal jaw fulcrumed in a transverse slot formed in said base to swing toward the post, said jaw being concaved 50 vertically on its inner side to partly overlap said post and having, at its upper end, an inward projection to overhang the interposed yarn and prevent its escape from the space between the post and the jaw during 55 the weaving operation.

3. A yarn-tensioning device for a self-threading shuttle embracing a vertical post and having its base portion secured in a socket in the bottom of the longitudinal 60 thread channel of the shuttle, said post being rounded on its inner side, an opposing vertical jaw fulcrumed in said base to swing about an axis lengthwise of the shuttle toward and away from the post, said 65 jaw being vertically concaved to partly fit around the inner side of the post, means for preventing the escape of the yarn from the space between the post and the jaw while guiding the yarn during the threading 70 operation into such space, a tensioning spring mounted in a transverse bore of the shuttle body, and a spring-compression adjusting screw mounted in said recess to vary the compression of the spring, sub- 75 stantially as described.

In witness whereof, I have subscribed the above specification.

GEORGE M. CHENEY.
